UNITED STATES PATENT OFFICE.

EDWARD D. PRIEST, OF SCHENECTADY, NEW YORK, ASSIGNOR TO GENERAL ELECTRIC COMPANY, A CORPORATION OF NEW YORK.

DYNAMO-ELECTRIC MACHINE.

No. 918,594.

Specification of Letters Patent.

Patented April 20, 1909.

Application filed February 13, 1907. Serial No. 357,120.

To all whom it may concern:

Be it known that I, EDWARD D. PRIEST, a citizen of the United States, residing at Schenectady, in the county of Schenectady, 5 and State of New York, have invented certain new and useful Improvements in Dynamo-Electric Machines, of which the following is a specification.

The space which is available for the reception of a dynamo-electric machine is often so limited that it is necessary to economize in the dimensions of the machine in every possible way without decrease in power. This is particularly true of motors 10 intended for railway purposes. These motors are mounted on the trucks of the cars or locomotives and can be allotted only a limited space, especially in the vertical direction. While railway motors are required 15 to be extremely compact, it is also essential that they may be taken apart readily without danger of producing disturbances which would affect their proper operation when again assembled.

20 The object of my invention is to provide a simple and effective arrangement whereby compactness, together with ease of assembly and replacement of the parts, is secured. To this end I so arrange the laminæ of the 25 armature core body that they are carried directly upon the armature shaft, namely, without the intervention of the sleeve or the like. The laminæ, which are arranged between the usual end-plates, are clamped between 30 shoulders on the shaft, one of the shoulders being preferably in the form of a nut so as to be adjustable along the shaft. By this arrangement the diameter of the 35 core body is reduced to a minimum, since all of the cross-sectional area is occupied by metal which is necessary either for mechanical strength or for the purpose of forming part of the magnetic circuit. It is often 40 necessary to be able to remove the armature from the shaft without disturbing the parts 45 of the armature itself or its connection with the commutator, and I therefore provide detachable bolts arranged to extend through longitudinal ventilating channels in the 50 laminæ and one of the end plates, whereby the clamping of the armature core may be effected temporarily independently of the

shaft. Furthermore, in order that the commutator or other current collector may be removed from the shaft with the armature 55 without disturbing the connections between the armature winding and the commutator, I provide one of the end-plates of the armature core with a laterally-projecting sleeve by which the current collector is centered. 60 In the preferred form of my invention I extend the sleeve so that the commutator is not only centered thereby, but is mounted on said sleeve.

The various features constituting my invention will be pointed out with particularity in the appended claims; but for a full understanding thereof reference may be had to the following detailed description taken in connection with the accompanying drawings, wherein—

Figure 1 is a longitudinal cross-section of a railway motor arranged in accordance with a preferred form of the present invention; Fig. 2 shows the armature with the temporary fastening means in place the shaft being ready for removal; Figs. 3 and 4 show details of the temporary fastening means; and Fig. 5 is a fragmentary view of a modification.

Referring to the drawing, 1 is the frame of a dynamo-electric machine which, in the drawings, is illustrated as an inclosed railway motor; 2 is the armature shaft mounted in suitable bearings 3 and 4 in the frame of the machine. The armature consists of a laminated core body 5 arranged between end members 6 and 7 and having suitable windings 8. These parts, except as hereinafter indicated, may take any usual or preferred forms, the particular forms illustrated being simply indicative of general type. Instead of mounting the laminæ of the armature core upon a sleeve, either connected to or separate from the end-plates, and thereby interposing useless metal in the structure, the laminæ are punched out so that they fit snugly upon the shaft, and, when assembled upon the shaft, are prevented from rotation relative thereto by means of a key 9 or other suitable device. When the armature is assembled upon the shaft the end-plate 7 abuts against a shoulder 10 on the shaft, while the outer end of the sleeve on the other end-plate is

engaged by a nut 11 screw-threaded upon the armature shaft so that upon turning the nut the armature is tightly clamped between it and the shoulder 10. The commutator or other current-collecting device 12 is centered by and is preferably mounted upon the sleeve or extension 13 projecting from one side of the end-plate 6, so that the connections to the commutator are not disturbed as long as the armature core members remain clamped together. Such an armature could not be removed from its shaft without disarrangement of its parts unless some means were provided for temporarily clamping it together. For this purpose I make use of bolts or other suitable fastening means which may be inserted through the ventilating channels in the core body so as to clamp the laminæ together independently of the shaft. In the motor illustrated, the armature core is provided with longitudinal ventilating channels 14 and transverse channels 15 connecting the channels 14 with the periphery of the armature. On the inner side of one of the end-plates, namely the plate 6, there are arranged in alinement with some or all of the longitudinal channels, screw-threaded sockets 16. The longitudinal channels may extend entirely through the end member 7 or this member may be made in the form of an armed spider as shown. Temporary clamping is effected by inserting bolts 17, extending through the entire core body, through the channels 14 and screwing them into the sockets 16, which are located in a shoulder on the inner side of the end member 6. The connection between the outer ends of the bolts and the core body may be effected in any suitable way but, in the construction illustrated, since the end member 7 is in the form of an armed spider, it is convenient to use as an abutment for the bolt heads an auxiliary end plate 18 which may be slipped upon the shaft and brought against the arms of the spider. The bolts are passed through openings 19 in the auxiliary plate, which register with the channels 14, the bolt heads resting against the outer side of the plate.

In Fig. 1 the motor is illustrated in its assembled form. In Fig. 2 the temporary clamping means is shown in place, while the clamping nut 11 on the armature shaft has been removed. It will be seen that the shaft may now be pressed out through the right-hand end of the armature without disturbing the armature or the commutator. When it is desired to again replace the shaft, the parts are assembled as shown in Fig. 2, and the nut 11 placed in position, whereupon the temporary clamp may be removed without disarranging any of the parts. Thus, during the operation of the machine, the longitudinal ventilating openings are entirely clear and fully serve their purpose as venti-

lating means. However, when it is desired to remove the armature from the shaft, these openings, which for the time being are idle, are made useful for receiving the temporary clamp. A minimum core diameter is therefore obtained without interference with the ease of removal and subsequent assembly of the armature upon its shaft.

In Fig. 5, I have shown a slightly modified arrangement. In this form of my invention the commutator 20, instead of being mounted upon a sleeve projecting from the end plate 21, is located directly upon the armature shaft 22. The end plate is provided with a short tubular projection 23 which extends into the interior of the commutator sleeve 24 for a short distance so as to center the commutator with respect to the armature. The armature and commutator are secured in place by means of the nut 25 which is screw-threaded upon the shaft and bears against the end of the sleeve 24. The temporary clamping bolts 26, in this form, pass entirely through the end plate 21 and are screw-threaded into the end of the commutator sleeve as shown.

What I claim as new and desire to secure by Letters Patent of the United States, is,

1. In a dynamo-electric machine, a shaft, a core body made up of laminæ mounted directly upon said shaft and a pair of end plates, a shoulder on said shaft engaged by one of said end plates, a nut screwed upon said shaft and engaging the other of said end plates to clamp the core body together upon said shaft, said core body having longitudinal ventilating channels extending through the laminæ and one of said end plates, a sleeve projecting from one of said end plates, a current collector centered by said sleeve, windings on said core body connected to said current collector, and detachable bolts arranged to extend through said channels for temporarily clamping the core body together independently of the shaft so that said shaft may be removed from said core body without disturbing the parts thereof or the connections of the windings with the current collector.

2. In a dynamo-electric machine, a shaft, a core body made up of laminæ mounted directly upon said shaft and a pair of end plates, a shoulder on said shaft engaged by one of said end plates, a nut screwed upon said shaft and engaging the other of said end plates to clamp the core body together upon said shaft, said core body having longitudinal ventilating channels extending through the laminæ and one of said end plates, a sleeve projecting from one of said end plates, a current collector centered by said sleeve, windings on said core body connected to said current collector, an auxiliary end plate fitting against one of said members and having

openings therein registering with said ventilating channels, and detachable bolts arranged to extend through said channels and the openings in said auxiliary end plate for 5 temporarily clamping said core body together independently of the shaft so that said shaft may be removed from said core body without disturbing the parts thereof

or the connections of the windings with the current collector.

10

In witness whereof, I have hereunto set my hand this 11th day of February, 1907.

EDWARD D. PRIEST.
